UNITED STATES PATENT OFFICE.

BENJAMIN BRODIDO, OF NEW YORK, N. Y., ASSIGNOR TO THE SUPERHEATER COMPANY,
OF NEW YORK, N. Y., A CORPORATION OF DELAWARE.

EXHAUST-STEAM INJECTOR.

Application filed October 30, 1923. Serial No. 671,810.

To all whom it may concern:

Be it known that I, BENJAMIN BRODIDO, a citizen of the United States, and resident of the borough of Manhattan, city and State 5 of New York, have invented certain new and useful Improvements in Exhaust-Steam Injectors, of which the following is a specification.

This invention relates to injectors and 10 particularly to that type of injectors shown in United States Patent No. 1,842,128, granted June 1, 1920, to James Metcalfe et al., wherein is disclosed an injector adapted to be operated by the exhaust steam from an 15 engine.

In this type of injector, a supplementary supply of live steam is used to augment the exhaust steam when the pressure of said exhaust steam falls below an amount sufficient 20 to ensure the proper functioning of the injector. In addition to the said supplemental supply of live steam an auxiliary supply of live steam is also provided for operating the injector, if necessary, when 25 the engine is not running. Heretofore it has been the practice to provide manually operable valves to control the admission of the steam through the supplemental and auxiliary steam inlets and due to the provision 30 of these manually operable valves it has been found that some engineers in order to avoid giving the required time and attention to the manipulation of the valves, will leave the valve turned on when there 35 is no necessity for doing so, thereby causing the waste of live steam which it is the primary purpose of the exhaust steam operated injectors to conserve.

The principal object of this invention is 40 to provide a new and improved construction of the type referred to by means of which the construction and operation of the device is considerably simplified and the admission of live steam to the injector 45 is automatically controlled by variations in the working conditions of the injector.

For the accomplishment of those and such further objects as will be apparent to those skilled in the art to which this invention 50 appertains, my invention consists in the construction, combination and arrangement of parts as shown in the various embodiments which are hereinafter more particularly described and are illustrated in the accom-

panying drawings forming a part hereof, 55 but it will be understood that changes, variations and modifications may be resorted to without departing from the spirit of my invention.

Referring to the drawings, Fig. 1 is a 60 central longitudinal section through an injector embodying my invention. Fig. 2 is a detail sectional view of a modified form of a pressure actuated device, and Figs. 3 and 4 are views similar to Fig. 1 of two 65 different modifications.

As shown in the drawings the injector consists of a casing 10; having a main steam exhaust nozzle 11, a water cone or preliminary mixing nozzle 12, a combining nozzle 13, a delivery nozzle 14, a live steam nozzle 15 and a further preliminary mixing nozzle 16 interposed between the combining nozzle 13 and the water cone 12, all as more particularly set forth in the 75 aforementioned Metcalfe et al. patent.

The live steam nozzle 15, according to my invention, is secured to and communicates with a valve casing 17 which is located within the exhaust steam passage 19, but which 80 casing will permit the passage of the exhaust steam about its outer sides from the valved inlet 20 to the main exhaust steam nozzle 11. Casing 17 is bored to provide a conduit 21, with which the pipe 22 communicates for supplying live steam, thus replacing the former live steam supplies heretofore employed, and which conduit 85 communicates with an enlarged chamber 24, through a plurality of elongated steam admission ports 25, cored out of said casing. 90

A valve 26 in the shape of a cylindrical plunger is slidably mounted within the valve casing 17 and its lower reduced end passes through a suitable aperture in a partition wall 27 of the valve casing 17, which partition wall divides the live steam chamber 24 from an exhaust steam cylinder 28. A piston head 29 slidably mounted in said cylinder 28 is adapted to be held in contact 100 with the lower face of the valve or plunger 26 by means of a coiled spring 30, one end of which spring bears against said piston head 29 and the other end of which is adjustably supported by an adjusting nut 31. Nut 31 is screwed into a cylinder head 32 which closes the end of cylinder 28 and is secured thereto by any suitable means. 105

A conduit 33 connects the lower end of cylinder 28 with the exhaust steam passage 19.

The operation of the injector shown in Fig. 1 is as follows, the pressure of the steam entering exhaust steam passage 19 will be communicated through conduit 33 to the lower face of piston head 29 (which it will be noted is of greater diameter than the top face of valve plunger 26) and will tend to raise piston head 29 and valve 26 against the pressure of the live steam in conduit 21. Spring 30 will be adjusted by means of the adjusting nut 31, so as to cause the valve 26 to completely close the ports 25 when the pressure of the exhaust steam is sufficient to insure continuity of the jet delivered by the injector. If the pressure of the exhaust steam should drop, the pressure of the live steam in conduit 21 will cause valve 26 and piston head 29 to move downwardly to open the ports 25 to an extent substantially proportional to the drop of the exhaust steam pressure; the pressure of the steam in conduit 21 decreasing as the extent of the opening of the ports 25 increases and the upward force of spring 30 increasing as the downward movement of the valve and piston head increases. It will be readily understood that the area of the ports 25 and the tension of spring 30 may be so proportioned as to obtain an automatic compensation for the drop of the exhaust steam pressure that will require the use of only a sufficient amount of live steam necessary to insure the proper operation of the injector.

In the form of the invention shown in Fig. 2 the piston head 29 and spring 30 are replaced by a movable spring metal diaphragm 40 to which is connected the valve plunger 26^a. Diaphragm 40 is clamped between a suitable shoulder 41, formed by counterbore 42 provided in the casing cylinder 28^a, and the cylinder head 32^a which is provided with screw threads to engage the cooperating screw threads of counterbore 42. An annular conduit 43 is provided between cylinder head 32^a and the cylinder casing, with which conduit the by-pass 33^a communicates, and a plurality of ports 44 lead from said conduit to the interior of the cylinder. The operation of the diaphragm in Fig. 2 will be similar to the operation of the piston head 29 shown in Fig. 1.

In the form of my invention shown in Fig. 3 the construction and operation of the injector are similar to that shown in Fig. 1 with the exception that instead of actuating the piston head 29 upwardly by the pressure of the exhaust steam, said piston is actuated by the pressure of the water within the delivery pipe 45 of the injector which leads to the boiler, and for this purpose, the cylinder 28 is connected by means

of the pipe 46 with said delivery pipe. As the combined jet of water and steam forced upwardly through the pipe 45 by the injector would tend to produce a suction within the pipe 46, a baffle 47 is arranged adjacent to the point of connection of pipe 46 to pipe 45 to minimize the production of a suction effect within pipe 46 by the velocity of the jet in pipe 45.

In the form shown in Fig. 4 the valve 26^b is actuated by the vacuum produced in the vacuum compartment 48 of the injector. A pipe 49 connects said compartment with a cylinder 28^b, similar to that shown in Figs. 1 and 3, but above the piston head 29^a, instead of below the same.

The valve 26^b is secured directly as by nut 50, to the piston head 29^a, and the cylinder head 32^b is provided with an aperture 51 to allow the atmospheric pressure to be exerted against the lower face of the piston head.

When the injector shown in Fig. 4 is operating, if the vacuum in the compartment 48 is not sufficiently high to insure the proper continuity of action, the pressure of the live steam against the top of valve plunger 26^b will cause the plunger 26^b and piston 29^b to be forced downwardly to open the ports 25. When sufficient vacuum is maintained in the compartment 48, the atmospheric pressure upon the lower face of piston head 29 will overcome the pressure of the live steam and cause the valve plunger to close ports 25, it being understood that the relative diameters of plunger 26^b and piston head 29 will be so proportioned as to secure the operation of the parts.

Various changes in the specific form shown and described may be made within the scope of the claims without departing from the nature of my invention.

I claim:

1. The combination with an exhaust steam injector having a plurality of conduits connected therewith for supplying water, exhaust steam from an engine, and live steam, to said injector, of means for automatically controlling the admission of live steam to said injector, said means comprising a valve for closing the live steam conduit, and fluid pressure actuated means in communication with the interior of said injector for controlling said valve in accordance with the working conditions within said injector.

2. The combination with an exhaust steam injector having an exhaust steam chamber therein and conduits connected with said chamber for supplying thereto exhaust steam from an engine and live steam, of means for automatically controlling the admission of live steam to said chamber, said means comprising a valve for closing the live steam conduit and fluid pressure actuated means in communication with said

- chamber for controlling the operation of said valve in accordance with variations of the pressure of the steam within said chamber.
5. 3. The combination with an exhaust steam injector having an exhaust steam passage therein and conduits connected with said passage to supply thereto exhaust steam from an engine and live steam, of means to control automatically the admission of live steam in accordance with variations in the pressure of the exhaust steam in said passage, said means comprising a cylinder, a conduit connecting said cylinder with said passage, a valve to control the admission of live steam to said injector and fluid pressure actuated means within said cylinder to cause said valve to be operated in accordance with variations in the pressure of the exhaust steam within said passage.
4. The combination with an exhaust steam injector having an exhaust steam passage therein and conduits connected with said passage to supply thereto exhaust steam from an engine and live steam, of means to control automatically the admission of live steam in accordance with variations in the pressure of the exhaust steam in said passage, said means comprising a cylinder, a conduit connecting said cylinder with said passage, a valve constructed and arranged to be opened by the pressure of the live steam for controlling the admission of live steam to said injector, and fluid pressure actuated means within said cylinder for causing said valve to be actuated automatically against the pressure of the live steam in accordance with variations in the pressure of the exhaust steam within said passage.
5. The combination with an exhaust steam injector having an exhaust steam passage therein and conduits connected with said passage to supply thereto exhaust steam from an engine and live steam, of means to control automatically the admission of live steam in accordance with variations in the pressure of the exhaust steam in said passage, said means comprising a cylinder, a conduit connecting said cylinder with said passage, a valve to control the admission of live steam to said injector and fluid pressure actuated means within said cylinder to be opened by the pressure of the live steam for controlling the admission of live steam to said injector, and fluid pressure actuated means within said cylinder to cause said valve to be actuated automatically against the pressure of the live steam in accordance with variations in the pressure of the exhaust steam within said passage.
6. In an exhaust steam injector having an exhaust steam passage, a conduit connecting said injector with a supply of live steam, said conduit being provided with a port to admit the live steam to said injector, a valve movably mounted in said conduit adjacent to said port to govern the extent of opening thereof, said valve constructed and arranged to be moved by the pressure of said live steam to open said port, a cylinder, a by-pass connecting said cylinder with said exhaust steam passage, and fluid pressure actuated means within said cylinder for causing said valve to be actuated automatically and thereby control the extent of opening of said port in accordance with the variations in pressure of the exhaust steam.
7. In an exhaust steam injector having a plurality of passages in which the working conditions of the injector vary, a conduit connecting said injector with a supply of live steam, said conduit being provided with a port to admit the live steam to said injector, a valve movably mounted in said conduit adjacent said port to govern the extent of opening thereof, said valve constructed and arranged to be moved by the pressure of the live steam to open said port, a cylinder, in communication with one of said passages, and fluid pressure actuated means within said cylinder for causing said valve to be actuated automatically and thereby control the extent of opening of said port in accordance with variations in the working condition within said passage.

BENJAMIN BROIDO.
